Primary Examiner—Clare E Heflin*(74) Attorney, Agent, or Firm*—Joseph J. Previto**CLAIM**

The ornamental design of a hand tool, as shown and described.

DESCRIPTION

FIG. 1 is a perspective view of my new design showing it in a folded position.

FIG. 2 is an end view thereof.

FIG. 3 is a plan view thereof.

FIG. 4 is a side view thereof.

FIG. 5 is another side view thereof.

FIG. 6 is another end view thereof.

FIG. 7 is a perspective view similar to FIG. 1 showing the foldable hand tool in an unfolded position.

FIG. 8 is an end view thereof.

FIG. 9 is a plan view thereof.

FIG. 10 is a side view thereof.

FIG. 11 is another side view thereof; and,

FIG. 12 is another end view thereof.
